US00D649933S

(12) **United States Design Patent**
Wang et al.

(10) **Patent No.:** US D649,933 S
(45) **Date of Patent:** ** Dec. 6, 2011

(54) **UNINTERRUPTIBLE POWER SUPPLY**

(75) Inventors: **Shuangfeng Wang**, Shenzhen (CN);
Yuanhuan Xiong, Shenzhen (CN)

(73) Assignee: **BYD Company Limited**, Shenzhen,
Guangdong (CN)

(**) Term: **14 Years**

(21) Appl. No.: **29/396,434**

(22) Filed: **Jun. 29, 2011**

(30) **Foreign Application Priority Data**

Dec. 31, 2010 (CN) 2010 3 0708530

(51) **LOC (9) Cl.** **13-02**

(52) **U.S. Cl.** **D13/110**

(58) **Field of Classification Search** D13/110,
D13/101, 112, 118, 123, 160, 164, 184, 199;
D14/188, 265, 354, 355; 307/18, 22, 30,
307/31, 125, 126, 150; 361/600, 601, 622,
361/679, 683; 363/141, 144, 146, 147

See application file for complete search history.

(57) **CLAIM**

The ornamental design for an uninterruptible power supply, substantially as shown and described.

DESCRIPTION

FIG. 1 is a front view of an uninterruptible power supply in accordance with the present design;

FIG. 2 is a rear view of the uninterruptible power supply;

FIG. 3 is a top view of the uninterruptible power supply;

FIG. 4 is a bottom view of the uninterruptible power supply;

FIG. 5 is a left side view of the uninterruptible power supply; and,

FIG. 7 is a perspective view of the uninterruptible power supply.

The broken lines shown represent unclaimed subject matter and form no part of the claimed design.

1 Claim, 5 Drawing Sheets

FIG. 1

FIG. 2

FIG. 3

FIG. 4

FIG. 5

FIG. 6
